UNITED STATES PATENT OFFICE.

CHARLES S. CONE, OF LA CROSSE, WISCONSIN.

STAMP-VENDING MACHINE.

1,407,639.

Specification of Letters Patent. Patented Feb. 21, 1922.

Application filed July 11, 1919. Serial No. 310,157.

To all whom it may concern:

Be it known that I, CHARLES S. CONE, a citizen of the United States, residing at La Crosse, in the county of La Crosse and State 5 of Wisconsin, have invented certain new and useful Improvements in Stamp-Vending Machines; and I do hereby declare the following to be a full, clear, and exact description of the invention, such as will enable 10 others skilled in the art to which it appertains to make and use the same.

My invention has for its immediate object to provide an improved machine for vending and mechanically delivering postage 15 stamps that are in rolls with the individual stamps partially separated by perforated lines. The improved machine, however, is not limited to the vending and delivering of postage stamps, but is capable of much more 20 general use, being adapted for the feeding and delivery of various devices, such as theater, or other tickets, for example, which are in ribbon form, transversely perforated or cross scored or marked at intervals.

25 In the following description, however, the machine will be described as designed for, and used to vend and deliver postage stamps. The roll of postage stamps is transversely perforated on lines between the individual 30 stamps.

One feature of my invention is directed to 35 an improved feeding device for feeding the stamps, or strip, by virtue of perforated lines. This novel feeding mechanism and other associated highly important novel devices and combinations of devices will be described in connection with the accompanying drawings, wherein like characters indicate like parts throughout the several views.

40 Referring to the drawings:

Fig. 1 is a front elevation showing the improved stamp vending machine, some parts being broken away;

45 Fig. 2 is a vertical section taken approximately on the line 2—2 of Fig. 1;

Fig. 3 is a fragmentary transverse vertical section taken approximately on the line 3—3 of Fig. 2;

Fig. 4 is a horizontal section taken ap-

proximately on the line 4—4 of Fig. 2, some 50 parts being broken away;

Fig. 5 is a vertical section taken approximately on the line 5—5 of Fig. 4, some parts being broken away;

Fig. 6 is a detail in horizontal section on 55 the line 6—6 of Fig. 5;

Fig. 7 is a section taken approximately on the line 7—7 of Fig. 3, some parts being removed;

Fig. 8 is a detail in horizontal section 60 taken approximately on the line 8—8 of Fig. 7;

Fig. 9 is a vertical section taken approximately on the line 9—9 of Fig. 4, some parts being broken away and some parts being 65 shown in full; and

Fig. 10 is a perspective view showing a modified form of the stamp or ribbon feeding drum.

The machine illustrated is a duplex 70 machine, that is, is adapted to feed the stamp from two laterally spaced rolls mounted on independent reels. There is an independent feed mechanism for each roll of stamps and each such mechanism is independently coin 75 controlled, but the two feed mechanisms have a common actuating device adapted to be rendered operative by the coin deposited in the one or the other, or both of the mechanisms.

80 Preferably, the mechanism is all, or practically all inclosed within a suitable casing. This casing, as shown, is rectangular and comprises a base portion 11, a top 12, connecting corner post 13, and glass side plates 85 14. The numeral 15 indicates a direction board which constitutes no part of the present invention, but, as shown, is secured to the rear of top 12 and rises therefrom. In Fig. 2, a weighing scale, indicated as an entirety 90 by the numeral 16, is applied on the base flange of the direction board 15, in position where purchasers of stamps may use the same.

Extending about centrally through the 95 casing and secured to the base and top, is a column 17, the upper end of which is threaded and provided with a nut 17^a. The sides

and top of the case are removable from the base when nut 17^a is removed. Column 17, on its front face, is formed with notches or serrations 18 that perform a function 5 hereinafter noted.

The ribbon-like rolls of stamps are indicated by the character γ , and, as shown, they are contained on depending reels 19. The reels 19 are rotatively mounted on the opposite ends of a transverse spindle or idle shaft 20, and are removable therefrom when outer cotter corners 21 are removable from the ends of said spindle. Spindle 20 is passed through perforations in the upper laterally spaced arms 22^a of a pair of bearing metal brackets 22 that are rigidly secured to vertically disposed coin troughs or channels 23. These coin channels 23 are open at front, and at their lower ends, have laterally turned base flanges 23^a bolted, or otherwise, rigidly secured to the base 11. Just below the extreme upper ends the trough channels 23 are provided with horizontally projecting flanges 23^b that are bolted, or otherwise, rigidly secured to a tie plate 24. Tie plate 24 extends under the front edge of top plate 12, is perforated to pass the threaded upper end of column 17 therethrough, and is normally clamped to the column by a nut 17^a but is not removable with the top plate, or with the casing proper.

From the reels 19, the stamp ribbon γ is passed downward against ribbon guiding plates 25 that have segmental portions 26 formed with internal clearance channels 26^a. Guide plate 25 has side webs 26^b, and each complete guide plate is secured to and located within a hopper-shaped supplemental bearing frame 27. These supplemental frames 27 are laterally spaced, at their upper side portions are rigidly connected to flanges of the bearing frame 22, preferably by screws 28, and at their lower portions, have depending brackets 27^a bolted, or otherwise, rigidly secured to the base 11.

Working rotatively within the concave portion of each guide plate 25 is a stamp or ribbon feeding drum 29. Each feed drum 29 is secured to its own shaft 30, and the two shafts 30 are axially aligned and rotatively mounted in the side webs of the respective guide webs 26^b and in the side webs of the frames 27, and at their inner ends, also, in a central bearing 31 that is rigidly secured to column 17 and to adjacent portions of the bearing frame 27.

Feed drum 29, for engagement with the perforations in the ribbon between individual stamps, is provided with sharp and small projecting teeth 32, shown as formed on the outer edges of thin metal bars 33 that are radially inset into the peripheral portion of said drum and extend parallel to the axis 65 thereof with the teeth 32 aligned to move

through the segmental channels 26^b of the guide plate 25. Here it should be noted that between the peripheries of the drum, and the concave surfaces of the guide plates 25, there is just sufficient clearance to permit the stamped ribbon to pass freely without friction but with the teeth 32 projecting through the perforations and into the clearance channels 26^a.

Here it should be noted that the drum shafts 30, at their outer ends, are provided with a knob 30^a (see particularly Fig. 6), by means of which, when the enclosing case is removed from the base, said drum may be manually rotated, at will.

Located just in front of the columns 17 is a vertically movable plunger 34, which, at its lower end portion, works with ample clearance through a plate 35 and is guided by a flange 36, which plate and flange project horizontally from the fixed bearing bracket 22. The upper portion of said plunger 34 works through and is guided by the fixed top guide plate 24 and, at its extreme upper end, is pivoted to the intermediate portion of an operating lever 37. Lever 37, at one end, is provided with a knob 38 adapting it to be easily depressed, while its short end is connected by a link 39 to a lug on the top plate 12.

Coiled spring 40 surrounds plunger 34 and is compressed between guide flange 36 and a yoke-like crosshead 41 that is rigidly secured to said plunger and is normally just below the top plate of the casing.

A pair of rack bars 42 are attached at their upper ends to the opposite ends of the crosshead 41, and these racks depend through and are guided for vertical movements by guide plate 35. There is one of these rack bars for each side or section of the machine, and each rack bar meshes with a spur pinion 43 that is mounted to rotate and slide on a short shaft 44 journaled in the central bearing 31 and in the adjacent side of the hopper-like bearing frame 27. At one end, pinion 43 has a half clutch 43^a, with which latter is engaged the forked lower end of shipper lever 45 that is intermediately pivoted to a vertically projecting arm 31^a of the central bearing 31.

Lower end of lever 45 is yieldingly pressed toward the left, in respect to Fig. 3, by a suitable support or coiled spring 46. An upwardly spring pressed lock dog 47 pivoted to the extreme upper end of arms 31^a works through the slotted upper end of each shipper lever 45 and is provided with a shoulder adapted to engage the extreme upper end of said lever and to hold the same normally in the position shown in Fig. 3.

Each shipper lever 45 has a tripping cam lug 48 that is adapted to be engaged by a cam flange 48' on the co-operating rack bar 42.

Secured to each shaft 44 is a spur gear 130

49 provided on its hub with a half clutch 49^a adapted to be engaged by the half clutch 43^a of the sliding pinion 43. Here it should be noted that said pinion 43 is a wide-faced 5 pinion adapted to maintain mesh with its co-operating rack bar 42 when slid to different axial positions on its shaft 44. The pinion 49 of each shaft 44 meshes with a spur gear 50 on the shaft 30 of the cooperating feed drum 29.

By the respective feed drums 29, the stamp ribbon is fed over the curved bottom of its cooperating hook-like bearing frame 27, and the stamps will be severed by the action of 15 a knife that cooperates with the extreme edge 27^a of said frame, as a shearing edge. The knives 51, of which there is one for each shearing edge 27^a, are flat blades which, at 20 their inner ends, are riveted or otherwise rigidly secured to a knife carrying head 52. This carrying head 52, as shown and provided, is a stamped metal structure, the intermediate portion of which is rigidly secured to the lower portion of the plunger 25 34 (see particularly Figs. 8 and 9).

Pivoted at its lower end, at 53, to the knife carrying head 52 for cooperation with one of each knife mechanism, are so-called 30 trip levers 54. The upper ends of these levers 54 are curved rearwardly and provided at their free upper ends with laterally projecting trip lugs or flanges 55 that cooperate with the free ends of the lever locking dogs 47 in a manner which will hereinafter be 35 described. The trip levers 54 are yieldingly pressed forward or toward the right, in respect to Fig. 7, by the ends of a spring 56 that is intermediately connected to the plunger 34 (see Figs. 7 and 8). At their intermediate portions, trip levers 54 are provided 40 with laterally projecting cam pins or lugs 57, and at their front edges, with forwardly projecting coin-engaging shoulders 58. Cam pins 57 cooperate with cam bars 59 rigidly 45 secured at their upper ends to bearing brackets 22. These cam bars 59 have vertical cam surfaces 59^a and curved cam surfaces 59^b which operate, as hereinafter described.

As the knives descend to sever the stamps, 50 they are engaged by the oblique edges of presser bars 60 pivoted at their upper ends at 61 to the arms 22^a of the respective bearing frames 22. The lower ends of presser bars 60 are shown as equipped with leaf 55 springs 62 that engage the backs of the coin channels 23 (see Fig. 7) and force the said lower ends of said presser bars toward the shearing edges 27^a.

As the stamp strips are fed to the shearing edges 27^a, they pass under the segmental flanges 63 of strip clamping levers 64 that are secured to a small common rock shaft 65 that extends through both bearing frames 27 and is journaled in the side plates there-

of. These levers 64, close to their pivots, 65 are provided with eccentric clamping edges 66 which, when said levers 64 are rocked to the right, in respect to Fig. 7, engage and press the stamp strips against the bottoms of the frames 27 adjacent to the shearing 70 edges 27^a thereof. Levers 64 are yieldingly pressed to the right, in respect to Fig. 7 by suitable springs 67. The upper ends of said levers 64 are curved or obliquely set and their free upper ends normally engage the rear faces of the respective knives 51. The action of these levers will be further considered later on.

In this preferred arrangement of the machine, the right hand stamp feeding drum 80 29 is arranged to simultaneously feed two two-cent stamps for each nickel deposited in the right hand coin channel, and hence, is, for each feed movement, given a half rotation, and the left hand stamp feeding drum 85 29 will be arranged to feed four one-cent stamps for each deposited coin or nickel, and hence, will be given a complete rotation. For the accomplishment of the above results, ratchet wheels 68 are secured to the 90 respective feed drum shafts 30 adjacent to the cooperating feed drums (see particularly Figs. 1, 5 and 6). For reasons above indicated, the right hand ratchet wheel 68 will have two diametrically opposite teeth 95 while the left hand shoulder wheel will have but one tooth.

For independent cooperation with these ratchet wheels, I provide downwardly spring pressed retaining dogs 69 pivoted to the adjacent sides of the frames 27 and having at their free ends, extended fingers 69^a that normally rest upon the backs of cooperating knives 51 and are thereby held raised and in inoperative positions. When the knives 100 are depressed, dogs 69 will follow until their shoulders engage an aligned tooth of the cooperating ratchet wheel 68, and thus backward rotation of the feed drum is positively prevented while the knives are operating. 110 To prevent over rotation of the stamp feeding drums in forward direction, leaf springs 70 are anchored at one end to the respective frames 27 with their free ends engaged with the respective gears 50.

When plunger 34 is depressed by a depression of the lever 37, crosshead 41, with its rack bars 42 and the knife carrying head 52 with the two knives 51, will be moved downward, as already indicated. To insure full 120 downward movements of the plunger and parts carried thereby, crosshead 41 (see Fig. 5) is provided with a centrally spring-held full stroke pawl 71. When plunger is depressed, dog 71 will yield in an upward direction and pass over the teeth or serrations 18, column 17, at an oblique angle thereto, which will prevent return movement of the

plunger until the said dog has been carried below the said serrations 18, whereupon the said dog will yield in a downward direction and permit return movements of the plunger 5 and the parts carried thereby.

When a coin X (see particularly Figs. 5 and 7), is inserted in one of the coin channels, it will drop therein until it is intercepted by a detaining spring 72 applied to 10 the back of said channel with its free end projecting into the same. Just before the coin is stopped by the detaining spring 72, it strikes the free lower end of a coin cut-off lever 73, that is intermediately pivoted to the 15 respective coin channel and has a free open end 73^a which is arranged to enter the upper portion of the said coin channel and prevents a second coin from being dropped into the channel until the previously deposited coin 20 has been forced further downward in the said channel by a subsequent depression of the operating plunger 34.

From the lower ends of the coin channels, the coins will pass through a slot 74 in base 25 11 and into a coin box 75 shown as contained within the said hollow base 11. At the extreme lower end of each coin channel, however, is a secondary coin intersecting spring 30 76 which is so located that there will always be several, say four deposited coins in the lower portion of each channel below the first or primary intersecting spring 72. These intersecting springs 72 and 76 will yield to 35 permit coins to pass under pressure produced, as hereinafter described, by depression of the operating plunger 34.

The several stamps will be delivered into inclined stamp receiving pockets 77 that are 40 open at the front end of the case for the removal of the stamps. Pivotaly mounted in each pocket 77 at 78 is a curved stamp intercepting blade 79 that is provided with an upstanding perforated lug 80. The lug 80 of each stamp intercepting blade 79 is loosely 45 pivoted to the lower end of a lever 81 that is intermediately pivoted at 82 to the adjacent bearing frame 22. The upper ends of levers 81 are shown as forked and are pivotally connected at 83 to the short lower ends 50 of upper levers 84 that are also pivoted to bearing frames 22. These upper levers 84, at their free upper ends, are provided with coin intercepting blades or fingers 85 adapted to 55 enter the upper portions of the respective coin channels (see particularly Fig. 5). Levers 81, at their lower rear edges, are provided with oblique cam surfaces 86 adapted to be engaged by the respective knives 51 when the latter are depressed.

60 Fig. 6 illustrates a modified form of stamp ribbon feeding drum or roller which comprises disk-like head portions 87 and an intervening body portion 88 that is rectangular in cross section. This angular body portion

is shown as provided with four sides, but 65 might be provided with more or less such sides, but should have quite sharp edges spaced to correspond to the distance between the stamps so that the said edges will bend the stamped ribbon on its perforated lines. 70

Operation: The operation of many of the devices above described has been made clear from the foregoing description. But the operation of the machine, as an entirety, may 75 be summarized as follows:

The coin to be deposited is assumed to be a nickel. If deposited in the right hand coin channel, the purchaser will obtain two two-cent stamps and if deposited in the left hand coin channel, the purchaser will receive four 80 one-cent stamps, this being in accordance with statements already made.

When a coin is deposited in a coin channel 23, it will drop therein until it is intercepted by spring 72 (see Fig. 7). In this position, 85 the coin also engages the lower end of the cut-off lever 73 and causes the upper end of said lever to move into the position shown in Fig. 5, so that it will prevent a second coin, at this time, from being dropped into the 90 said channel beyond the position shown at the top in Fig. 5. The coin deposited and held by the intercepting spring 72, as shown in Fig. 7, will be in position to be engaged by the driving lug 58 of the so-called tripping lever 54 in the position shown in Fig. 7. The coin will drop in the channel past the 95 said driving lug 58, because the said lever 54 is then held in a retracted position by engagement of its cam pin 57 with the vertical 100 cam surface 59^a of fixed cam bar 59.

The stamp feeding, cutting and delivering action is produced by a downward movement of the main plunger 34, and this plunger is forced downward by depressing the knob 38 105 of plunger lever 37. If no coin is deposited in the channel, as shown in Fig. 7, and plunger 34 is depressed, as stated, there will be no feeding of a stamp strip, for the following reasons. Tripping lever 54 is pivoted 110 to knife carrier head 52, which, in turn, is secured to the lower portion of plunger 34, and hence, the said tripping lever, regardless of whether or not a coin is deposited, will be carried downward with the said 115 plunger. When no coin is in position, as shown in Fig. 7, and the said parts are moved downward, as stated, cam pin 57 of lever 54 will immediately move below cam surface 59^a and will follow cam surface 59^b, 120 thereby carrying trip lug 55 forward, or to the right, in respect to Fig. 7, to a point forward of the free end of lock dog 47, so that the said lock dog will be left in this operative position shown in Fig. 3 and shipper 125 lever 45 will hold cooperating clutch 43^a in its inoperative position retracted from half clutch 49^a. If, however, the coin α is de-

posed, as shown in Fig. 7, and the plunger and other parts noted are depressed, as stated, then cam pin 57, on leaving the lower portion of vertical cam surfaces 59^a, will 5 move slightly forward or toward the right and just far enough to carry the tripping lug 55 over the free end of the cooperating lock dog 47, and the said tripping lever 54 will be stopped in this position by engagement of its lug 58 with the upper edge of coin α . Hence, further depression of said 10 plunger and the said tripping lever, lug 58, acting on the coin, will force the same below the intercepting spring 72; and thereupon still further downward depression of the said parts will carry cam pin 57 into engagement with the lower portion of cam surface 59^b, and the latter will cam the said lever 54 rearward or toward the left, far 15 enough to disengage lug 59 from the coin, leaving the coin free to fall against lower intercepting springs 76, or onto other coins held in the lower portion of the channel by said spring 76. The statements above made 20 are, of course, true, in respect to both sides of the machine. In the above arrangement of the machine, coins may be simultaneously deposited in both channels and the delivery of stamps may be simultaneously made from 25 both sides of the machine, or said feeding operations may be entirely independent and take place at different times.

When shipper levers 45 are released from lock dogs 47, springs 46, acting on said 30 levers, shift pinions 43 on shafts 44, thereby causing half clutch 43^a to engage half clutch 49^a, and thus connect the respective feed drums 29 through the said gears, so that they will be rotated by further downward 35 movements of the plunger and racks, and this, of course, produces the feed movements of the stamp ribbons. When the said racks nearly reach the limit of their downward movements, cam surfaces 48' come into action 40 on cam lugs 48 and thereby force the respective shipper levers 45 back to their normal position shown in Fig. 3, and in such positions, the said shipper levers will then be again locked by automatic engagement 45 therewith of their respective feed dogs 47.

The knives 51 are forced past the shearing edges 27^a to receive the stamps on the perforated lines between the stamps, approximately at the limit of the downward 50 movement of the plunger 34. The said knives will be pressed against said shearing edge by the spring pressed bars 60. Also, and as already described, as the knives approach their cutting positions, the stamp 55 strip will be gripped by the eccentric portions 66. Moreover, as the knives approach their lowermost positions, they act on the oblique edges 86 of levers 81 and cause two actions, towit, they move intercepting 60 blades 85 into the upper portions of the re-

spective coin channels 23 and rock the stamp intercepting blade 79 downward, so that it will intercept and cover up the severed stamps and thus eliminate the possibility of stamps, other than those punched, from 70 being pulled from the roll by hand manipulation, or otherwise.

As already indicated, this so-called stamp vending machine is not limited to the vending of stamps in ribbon or roll form, but 75 is capable of much wider range of usage. For instance, it is customary to sell motion picture tickets in ribbon form. This machine is well adapted for the vending and delivery of such tickets. 80

What I claim is:

1. A machine of the kind described comprising a ribbon feeding drum having ribbon engaging devices spaced circumferentially thereof to correspond to and engage 85 with the parting lines between sections of such ribbon, a ribbon guide co-operating with said feed drum and terminating in a shearing edge, a knife co-operating with said shearing edge, a ribbon clamp movable to 90 operative and inoperative positions co-operating with said ribbon guide, and a manually operated connection operative to move said feed drum while said knife and clamp are inoperative and to operate said knife 95 and clamping devices while said drum is stationary.

2. In a machine of the kind described, the combination with a ribbon feeding device including a feed drum for direct action on 100 the ribbon, of a manually operated plunger carrying a knife for severing the ribbon sections, a rack movable with said plunger, a driven half clutch gear connected to said feed drum, a driving half clutch gear connected to said rack and under yielding strain to engage said driven half clutch, a shipper lever normally operative to hold said half clutches disengaged, a lock dog normally holding said tripper lever in the normal position stated, and means for causing said half clutches to be engaged under movements of said plunger and rack. 110

3. In a machine of the kind described, the combination with a ribbon feeding device 115 including a feed drum for direct action on the ribbon, of a manually operated plunger carrying a knife for severing the ribbon sections, a rack movable with said plunger, a driven half clutch gear connected to said 120 feed drum, a driving half clutch gear connected to said rack and under yielding strain to engage said driven half clutch, a shipper lever normally operative to hold said half clutches disengaged, a lock dog normally 125 holding said tripper lever in the normal position stated, a yieldingly pivoted tripping lever associated with said plunger and normally inoperative on said lock dog but operative when said tripping lever is held in a 130

predetermined position, to trip said lock dog to thereby cause engagement of said half clutches with the resulting driving of said feed drum.

- 5 4. In a machine of the kind described, the combination with a ribbon feeding device including a feed drum for direct action on the ribbon, of a manually operated plunger carrying a knife for severing the ribbon sections, a rack movable with said plunger, a driven half clutch gear connected to said feed drum, a driving half clutch gear connected to said rack and under yielding strain to engage said driven half clutch, a shipper lever normally operative to hold said half clutches disengaged, a lock dog normally holding said tripping lever in the normal position stated, a yieldingly pivoted tripping lever associated with said plunger and normally inoperative on said lock dog but operative when said tripping lever is held in a predetermined position, to trip said lock dog to thereby cause engagement of said half clutches with the resulting driving of said feed drum, and means for disengaging said half clutch by continued movement of said plunger.
- 10 5. In a machine of the kind described, the combination with a ribbon feeding device including a feed drum for direct action on the ribbon, of a manually operated plunger, a knife operated by said plunger, a rack moved by said plunger, a driven half clutch connected to said feed drum, a sliding pinion driven by said rack and having a half clutch engageable with said driven half clutch, a yieldingly pressed shipper lever operative to shift said half clutch, a yielding lock dog normally operating on said shipper lever to hold said half clutches disengaged, and means operative to trip said dog and release said shipper lever when said plunger and rack are depressed.
- 15 6. In a machine of the kind described, the combination with a ribbon feeding device including a feed drum for direct action on the ribbon, of a manually operated plunger, a knife operated by said plunger, a rack moved by said plunger, a driven half clutch connected to said feed drum, a sliding pinion driven by said rack and having a half clutch engageable with said driven half clutch, a yieldingly pressed shipper lever operative to shift said half clutch, a yielding lock dog normally operating on said shipper lever to hold said half clutches disengaged, and means operative to trip said dog and release said shipper lever when said plunger and rack are depressed, said means comprising a dog engaging element carried with said rack, said shipper lever having a cam lug and rack having a cam flange, which lug and flange are operative to force said shipper lever to normal position and disengage said clutch

members after the proper feed movement 65 has been given to said drum.

7. In a machine of the kind described, the combination with a ribbon feeding device including a feed drum for direct action on the ribbon, of a manually operated plunger, a knife operated by said plunger, a rack moved by said plunger, a driven half clutch connected to said feed drum, a sliding pinion driven by said rack and having a half clutch engageable with said driven half clutch, a yieldingly pressed shipper lever operative to shift said half clutch, a yielding lock dog normally operating on said shipper lever to hold said half clutches disengaged, and means operative to trip 80 said dog and release said shipper lever when said plunger and rack are depressed, said means comprising a pivoted tripping lever connected to move in one direction with said plunger and operative in a predetermined position to trip said dog and release said shipper lever.

8. In a machine of the kind described, the combination with a ribbon feeding device including a feed drum for direct action on the ribbon, of a manually operated plunger, a knife operated by said plunger, a rack moved by said plunger, a driven half clutch connected to said feed drum, a sliding pinion driven by said rack and having a half clutch engageable with said driven half clutch, a yielding lock dog normally operating on said shipper lever to hold said half clutches disengaged, means operative to trip said dog and release said shipper lever when 90 said plunger and rack are depressed, and a fixed cam operative on said shipper lever, normally to permit a movement thereof which will render the same inoperative on said lock dog.

9. In a machine of the kind described, the combination with independent ribbon feeding devices, of a common operating plunger, means whereby, at will, either or both of said feed devices may be rendered 110 operative under movement of said plunger, and knives operated by said plunger to sever the sections of the ribbon, the said feed devices having different but predetermined ribbon feeding actions.

10. In a machine of the kind described, the combination with a ribbon feeding device, including a feed drum, a manually operated knife equipped plunger for severing the ribbon sections, a clutch connection 120 between said plunger and drum for operating the latter, a stripper lever normally operated to disengage the clutch members, a lock dog normally holding said stripper lever in position, and means for causing the 125 clutch members to be engaged under movement of said plunger.

11. A machine of the class described hav-

ing in combination, a ribbon feeding device including a drum for acting directly on the ribbon, a manually operated plunger, a rack movable with said plunger, a driven 5 half clutch gear connected to said feed drum, a driving half clutch gear connected to said rack and normally yieldingly urged to engage said driven half clutch, means normally held in position to maintain said

half clutches disengaged, and means for 10 causing said half clutch to be engaged under movement of said plunger and rack.

In testimony whereof I affix my signature in presence of two witnesses:

CHARLES S. CONE.

Witnesses:

M. B. AIKEN,
R. SKAILAND.
